UNITED STATES PATENT OFFICE.

LOUIS A. LARSON, OF MINNEAPOLIS, MINNESOTA.

THERMO-ELECTRIC HEAT-REGULATING SYSTEM.

1,157,112.

Specification of Letters Patent.

Patented Oct. 19, 1915.

Application filed February 16, 1914. Serial No. 819,057.

To all whom it may concern:

Be it known that I, LOUIS A. LARSON, a citizen of the United States, residing at Minneapolis, in the county of Hennepin and State of Minnesota, have invented certain new and useful Improvements in Thermo-Electric Heat-Regulating Systems; and I do hereby declare the following to be a full, clear, and exact description of the invention, such as will enable others skilled in the art to which it appertains to make and use the same.

My invention relates to thermo-electric heat regulating systems, and particularly to those in which an electric motor is controlled by a thermostat and affords the power for operating the dampers of the furnace or other heater.

Generally stated, the invention consists of the novel devices and combinations of devices hereinafter described and defined in the claims.

In the accompanying drawings which illustrate the invention, like characters indicate like parts throughout the several views.

Referring to the drawings: Figure 1 is a diagrammatic view illustrating the improved system; Fig. 1^a is a view corresponding to Fig. 2 but showing certain additional devices; Fig. 2 is a detail partly in elevation and partly in section showing the fixed contacts of the three-wire thermostat circuit; Fig. 3 is a plan view with some parts in section, showing the electric motor transmission mechanism and various associated devices, which parts are mounted on or within a suitable casing and constitute what may be treated as the power mechanism of the system; Fig. 4 is a vertical section taken on the irregular line x⁴ x⁴ on Fig. 3; Fig. 5 is a diagrammatic view in elevation illustrating connections for operating the draft and check dampers of a furnace; and Fig. 6 is a detail in plan showing a modified construction.

Referring first, particularly to Figs. 3 and 4, the numeral 1 indicates a suitable supporting case shown as provided with two-part casing 2—3, the section 2 being permanently secured thereto and the section 3 being removable. Mounted on the base 1 within the casing is a small electric motor 4, the armature shaft 5^a of which carries the pinion 5. The numeral 6 indicates a motor driven shaft journaled in suitable bearings on the

casing 2—3 and provided at its outer ends with crank arms 7 that stand 180 degrees apart and are adapted to operate the draft and check dampers of a furnace in the usual way through the customary connections. In the diagrammatic view in Fig. 5, one of the arms 7 is connected by a cable a to the pivoted draft damper b of the boiler or furnace c, while the other arm 7 is connected by a cable d to the check damper e of the said furnace. The cables a and b, respectively, run over suitable guide sheaves f and g. The dampers b and e, by successive half rotations of the crank arms 7 will be alternately opened and closed in reverse order in a manner well understood. The shaft 6 carries a large spur wheel 8 that meshes with a small pinion 9 carried by a counter shaft 10 journaled in bearings 11—12, respectively, on the base 1 and case section 2. Said shaft 10 also carries a large spur gear 13 that meshes with a spur pinion 14 secured to the hub of a spur gear 15. The combined gear and pinion 14—15 have a spindle 16 journaled in a U-shaped arm 17 that is pivoted on the shaft 10, so that the pinion 14 will maintain proper mesh with the said gear 13 when the arm 17 is moved upward and downward. By upward and downward movements of the arm 17, the gear 15 is adapted to be moved into and out of mesh with the pinion 5 on the armature shaft of the motor 4. Here it may be incidentally noted that on one side of the arm 17 is a leaf spring 18, the end of which frictionally engages the adjacent face of the gear 15 and acts as a light friction brake putting slight drag on the said gear for the purpose which will hereinafter appear.

The pivoted supporting arm 17 constitutes one of the elements of a so-called gear coupling device for moving the gear 15 into and out of mesh with the pinion 5, but this gear coupling device or mechanism in its preferred form, also includes the following elements, to-wit: The numeral 19 indicates an armature which, as shown, is pivoted to the bearing 12 and is subject to an electromagnet 20 secured on the base 1. The free end of the arm 17 is connected to the armature 19 by a spring connection 21 which is of such strength that it will cause the said arm to move the said armature under ordinary conditions. If the ends of the teeth of the gear 15 should engage ends of the teeth of pinion 5, when the former is drawn

2
down, the spring 21 will yield and permit the armature to be drawn down by the magnet and the motor started, and subsequently, will cause the gear teeth to go into proper mesh. A spring, which, as shown, is of the "Sear" type, and is indicated by the numeral 23, is connected at its upper end to the free end of the arm 17 and at its lower end to a bearing bracket 24 secured to the case section 2. As shown, this spring 23 has an extended arm 23^a that works in a perforation in the end of the arm 17, with sufficient play to permit the gear 15 to be moved into and out of mesh with the pinion 5. The spring 23 normally holds said gear 15 out of mesh with said pinion 5. When the magnet 20 is energized, it will throw down the armature 19 and with it the arm 17, thereby holding the gear 15 in mesh with the pinion 5 as long as the said magnet is energized and not longer.

In Figs. 1 and 2, the numeral 25 indicates a thermostat of the usual construction, which controls a three-wire circuit and has the customary vibratory theremally actuated contact 26 that works between and is adapted to alternately engage with relatively fixed contacts 27 and 28. In the customary arrangement, the thermostat 25 is, of course, located in the room, the temperature of which is to be maintained, and the motor and other parts shown in Figs. 3 and 4 will be usually located in the basement in the vicinity of the furnace which is to be controlled.

The numerals 29, 30 and 31, respectively, indicate the three-wires of the circuit directly controlled by the thermostat, and these three wires, respectively, lead from the contacts 26, 27 and 28 and lead the fixed contacts 32, 33 and 34, which, as shown, are secured to an insulating plate 35 located adjacent to one face of the gear 8, and, as shown, secured to the inner surface of the case section 7. The lead or wire 29 is used with both sides of the three wire thermostat controlled circuit, that is, may be assumed to be the common return for the circuit formed through the wires 30 and 31, and interposed therein is a battery 36, or other suitable source of electrical energy. Also, the gear coupler operating mechanism 20 and the electric motor 4 are interposed in the said lead 29 and thus connected in series.

55 The gear 8 carries a traveling contact 37 which, as shown, is secured to an insulating plate 38 on the said gear and has a body portion that always maintains engagement with the fixed contact 32. The crank shaft 6, and hence, the gear 8 are arranged to be intermittently given half rotations and the arrangement of the contacts 32, 33, 34 and 37 is such that in one stationary position of the said gear 8, the contact 37 will engage with the contact 33 and in the other position,

with the contact 34. Otherwise stated, the contact 37 alternately connects the opposite sides 30-41 of the thermostat circuit, to the common lead 29. The exact manner in which this action takes place under varying 70 temperature is well known, but it may be here stated that the thermostat contact 26 is moved to regulate the furnace for higher temperature, the circuit will be closed through the lead 30 for example, while when 75 the said contact 26 moves to regulate the furnace for lower temperature, said circuit will be closed through lead 31, but in both instances, through the battery 36, magnet 80 and motor 4.

The numeral 38^a indicates a shunt across the common lead 29 between the battery or source of electrical energy 36 and the thermostat 25, and the important purpose of which will presently appear. This shunt 38^a 85 is normally opened but is adapted to be closed by engagement of the vibratory contact lever 39 with a relatively fixed contact 40, both of which contacts, as shown, are supported by a bearing plate 41 of insulating material located adjacent to the inner face of the gear 8. The contact lever 39, as shown, is pivotally connected to the insulating plate 41 by a stud 42 that is equipped with a thumb nut 43 and a spring 44, which latter tends to frictionally hold the said lever 39 in either position in which it may be set. The inner end of the contact lever 39 is adapted to be engaged by diametrically opposite pins 45, and the outer end 100 thereof, by diametrically opposite pins 46, which pins or projections are carried on the gear 8.

The operation of the mechanism above described is substantially as follows: Figs. 3 105 and 4 indicate the normal position of the parts therein shown, at which time the circuit leading from the battery 36 is open so that the magnet 20 is deenergized and the motor 4 is idle. If the thermostat contact 110 26 now moves for engagement with the contact 28, while the contact 37 is in engagement with the contact 34, the battery circuit will be closed through the magnet 20 and motor 4, as follows: through wire 29, contacts 32, 37 and 34, from thence, through lead 31 back to thermostat contact 26. When the battery circuit is thus closed, the motor will be started into action and simultaneously therewith, the armature 19 120 will be thrown down, carrying with it the supporting arm 17 and thereby throwing the gear 15 in mesh with the pinion 5 on the check of the motor armature. This will cause the motor to rotate shafts 10 and 6 and gears 13 and 8, and this movement will continue until the shaft 6 and its arm 7 have been given a half rotation or movement through 180 degrees. The initial movement of the gear 8 will bring one of the pins 45 125 130

into engagement with the upper end of the contact arm 39 and will force the latter into engagement with the fixed contact 40, thereby closing the battery circuit through the 5 shunt 38^a, and in effect, cutting out the thermostat from the battery, motor and magnet circuit. The contact 37 should maintain engagement with the contact 34 until the shunt 38^a has thus been closed, and immediately thereafter it should be out of contact therewith, so that the thermostat is actually cut out.

Just before the gear 8 completes its half rotation, just noted, one of the pins 46 will 15 engage the lower end of the contact arm 39 and force the said arm out of engagement with the contact 40 and thereby open the shunt circuit and break the battery circuit through the magnet 20 and motor 4. When 20 this circuit is thus broken, the magnet being deenergized, will permit the spring 23 to raise the supporting arm 17 and thereby carry the gear 15 out of mesh with the pinion 5. This permits the transmission gears 25 and crank shaft 6 to immediately stop while the motor continues to run under its own momentum until it gradually stops without jar or strain, to the high speed armature thereof, or to the gear driven thereby. 30 When the gear 8 stops its lower pin 46 will have moved only slightly beyond the lower end of the contact lever 39 (see Fig. 4). When the gear 8 stops in the position just noted, the contact 37 will be shifted over into 35 engagement with the contact 33, so that the battery circuit through the thermostat magnet and motor cannot be again closed by the thermostat until its contact 26 moves into engagement with the fixed contact 27. Thus 40 it will be seen that the three-wire circuit is alternately closed first on one side and then on the other by the moving contact 37, and that during all but the initial movement, the current is delivered to the motor and magnet 45 through the shunt circuit, while the thermostat is cut out of the circuit. The friction brake or spring 18 already described, acts on the gear 15 to cause the transmission gears to quickly stop when 50 they are disconnected from the motor, but as they move slowly, their momentum would not carry the gears far even if this retarding device were not provided.

The motor may be directed from the 55 transmission mechanism in a good many different ways. I believe the separation of the gears to be the best way of accomplishing this, but it may be accomplished by a clutch such as shown in Fig. 6.

Referring to Fig. 6, the numeral 5^a indicates the pinion which in this instance, is loose on the motor armature shaft 5^b and is provided with a half clutch 47 that is adapted to be engaged with a half clutch 48 carried to rotate with but mounted to slide on

the said armature shaft 5^b, and adapted to be moved by a shipper lever 49 that is normally retracted by a spring 50 and is provided with an armature 51 subject to a magnet 20^a. Obviously, the spring 50 normally holds the half clutch 48 disengaged from the half clutch 47 and when the magnet 20^a, which will be in the lead 29, is energized, it will attract the armature 51 and force the half clutch 48 into engagement with the half clutch 47.

In Fig. 1^a, and also in Fig. 3, I have shown a device whereby the motor may be thrown into action at will, so as to operate the dampers of the furnace independently 80 of the thermostat. This device comprises three pairs of fixed contacts 52, 53 and 54 and a pivoted contact 55, and it includes certain shunt circuits arranged as diagrammatically shown in Fig. 1^a. Normally, or 85 when the thermostat is operative to control the motor, the contact 55 will close the circuit between the contacts 54 which are located in the common lead 29. When it is desired to operate the motor at will, independently of the thermostat, the contact 55 will be turned either into a position to close the circuit between the contacts 52 or between the contacts 53. When the contact 52 is moved to connect the contacts 53, a shunt 95 from the wire 31 will be connected across the wires 31 and 29, through wires 56 and 57; and when the contact 55 connects the contacts 52, the shunt across the wires 30 and 29 will be closed through wires 58 and 57. 100 To operate the motor, the connection between the contacts 53 must be made while the contact 37 is in engagement with the contact 34, or it must be made by connecting the contacts 52 while the said contact 37 is 105 in engagement with the contact 33.

As shown in Fig. 3, the contacts 52, 53 and 54 are secured on an insulating plate 59, and the contact 55 is provided with a stem 60 having at its outer end an operating arm 61. 110 Also, a coiled spring 62 applied on the stem 60 between a shoulder thereof and the relatively fixed plate 59 tends to hold the contact 55 in any one of the several positions in which it is adapted to be set.

What I claim is:

1. In a thermo-electric heat regulator, the combination with an electric motor and a transmission mechanism driven thereby, of a thermostat, electric circuits and automatic switches for controlling said motor by opening and closing the motor circuit, automatic means for mechanically disconnecting said motor from said transmission mechanism, when the latter has been given its interval of movement, and an electro-magnet in the motor circuits operative to couple said motor to said transmission mechanism when the motor circuit is closed.
2. In a thermo-electric heat regulator, the

combination with an electric motor and a transmission mechanism driven thereby, of a thermostat, electric circuits and automatic switches for controlling said motor, means 5 for automatically disconnecting said motor from said transmission mechanism, when the latter has been given its interval of movement, and a frictional retarding device or 10 brake operative on certain of the movable elements of said transmission mechanism to assist in stopping the same when the motor is disconnected therefrom.

3. In a thermo-electric heat regulator, the combination with an electric motor and a 15 transmission mechanism driven thereby, of a thermostat, electric circuits connecting said motor and thermostat with a source of electrical energy, and an automatic reversing switch and a shunting switch, both operated by said transmission mechanism, the 20 said reversing switch operating under the control of said thermostat to start said motor into action and said shunting switch operating subsequently to short-circuit the motor 25 circuit and cut out said thermostat, the said transmission mechanism serving to intermittently reverse the action of said reversing switch, and to leave said shunt switch open when said transmission mechanism is at rest.

4. In a thermo-electric heat regulator, the combination with an electric motor and a transmission mechanism driven thereby, of a thermostat, electric circuits connecting 35 said motor and thermostat with a source of electrical energy, a reversing switch in the thermostat operated alternately by said transmission mechanism, a shunt switch in a shunt across the motor circuit, and devices 40 carried by one of the movable elements of said transmission mechanism operative on said shunt switch to close the same by the initial movement of said transmission mechanism and to again open the same by the 45 final movement of said transmission mechanism.

5. In a thermo-electric heat regulator, the combination with an electric motor and a transmission mechanism driven thereby, of 50 a thermostat, electric circuits connecting said motor and thermostat with a source of electrical energy, a reversing switch in the thermostat operated alternately by said transmission mechanism, a shunt switch in a shunt across the motor circuit, devices carried 55 by one of the movable elements of said transmission mechanism operative on said shunt switch to close the same by the initial movement of said transmission mechanism and to again open the same by the final 60

movement of said transmission mechanism, a normally inoperative coupling for connecting said motor to said transmission mechanism, and an electro-magnet in the motor circuit operative on said coupling device to connect said motor to said transmission mechanism while, and only while the motor circuit is closed. 65

6. In a thermo-electric heat regulator, the combination with an electric motor and a 70 transmission mechanism driven thereby, of a thermostat, electric circuits connecting said motor and thermostat with a source of electrical energy, and an automatic reversing switch and a shunting switch, both operated 75 by said transmission mechanism, the said reversing switch operating under the control of said thermostat to start said motor into action and said shunting switch operating subsequently to short-circuit the motor circuit and cut out said thermostat, and auxiliary circuits and a manually operated switch co-operating with a motor circuit to render the motor operative independently 80 of said thermostat. 85

7. In a thermo-electric heat regulator, the combination with an electric motor and a transmission mechanism driven thereby, of a thermostat, electric circuits and automatic switches for controlling said motor, a yielding retracted support for one of the gears 90 of said transmission mechanism, a magnet in the motor circuit, an armature subject to said magnet, and a yielding connection between said armature and gear support 95 whereby said motor will be coupled to said transmission mechanism, while said motor circuit is closed.

8. In a damper controlling mechanism, a rotary member, a damper, means actuated by the rotary member for operating the damper, a pivoted device, a driving shaft, a gear rotatable with the driving shaft, a gear carried by said pivoted device and movable therewith into and out of engagement with the driving shaft gear, means connected with the gear on the pivoted device for rotating the rotary member, thermostatically controlled means including an electric circuit, and a switch in said circuit for operating said pivoted device, and means actuated by said rotary member for operating said switch. 100 105 110

In testimony whereof I affix my signature in presence of two witnesses.

LOUIS A. LARSON.
